UNITED STATES PATENT OFFICE.

FREDERICK BREDEL, OF NEW YORK, N. Y.

AUTOMATIC GAS-GOVERNOR.

SPECIFICATION forming part of Letters Patent No. 380,743, dated April 10, 1888.

Application filed November 17, 1887. Serial No. 255,421. (No model.)

To all whom it may concern:

Be it known that I, FREDERICK BREDEL, a subject of the Emperor of Germany, residing at New York city, in the county of New York and State of New York, have invented certain new and useful Improvements in Automatic Gas-Governors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to pressure regulators or governors for gas or similar fluids; and it has for its object to provide a governor of improved construction, which may be so adjusted as to obtain an automatic variation of 20 pressure in exact accordance with the variations of consumption in the plant to which it may be applied. Regulators for gas governors have been operated by means of weights arranged upon a proper support, so as to bear 25 upon the valve-stem, and adjusted by the addition or removal of weights from time to time as the consumption varies.

By the use of my improved form of governor the trouble incident to placing and removing the weights will be entirely obviated, and a steady and uniform variation in pressure will be maintained.

To these ends, and to such others as the invention may relate, the same consists in the 35 peculiar combinations and in the novel construction, arrangement, and adaptation of parts, all as more fully hereinafter described, shown in the accompanying drawings, and then particularly defined in the claims.

40 In the drawings, Figure 1 is a side elevation, partly in section, of a gas-governor embodying the principles of my invention. Fig. 2 is a side elevation, partly in section, of the automatic pressure-adjuster. Figs. 3 and 4 are diagrams showing the operation of the arm-adjusting mechanism.

Reference being had to the details of the drawings, A represents the main leading from the gas-holder and the interior pipe, and A' 45 represents the service-main.

B is the cylindrical wall or casing of the

water-tank, and B' the float-chamber, which is of well-known construction, excepting in certain details, which will hereinafter be more fully explained.

55 C represents a conical valve-body, bolted at its lower edge to the outwardly-extending flange C', formed upon the upper end of the service-main A', and provided at its upper edge with an outwardly-projecting flange, C², 60 which serves as a stop for the valve C³ at the outlet of the valve-chamber C⁴.

D is a valve-dome bolted securely to a flange formed at the top of the float-chamber B'. The upper edge of the valve-chamber C⁴ is enlarged and substantially conical in form, as shown, and is provided at its lower end with the pipe or extension C⁵, opening at its lower end into the interior of the float-chamber.

65 E is a plate or weight-holder, which is secured to the lower edge of the spool or drum E², through the center of which passes the vertical shaft E³, the lower portion of which is screw-threaded.

70 E⁴ is an adjusting-wheel mounted upon the screw-threaded portion of the shaft E³ and resting upon a flange upon the cover of the valve-dome.

75 F F are uprights bolted to the upper edge of the water-tank, and F² are arms, carrying at their lower ends the shafts F³, which are journaled between the vertical arms of the uprights F. The opposite ends of the arms are bifurcated, as shown, and within their bifurcations and similar ones upon the outer 80 ends of the arms G are journaled the wheels G², upon which rests the plate E, carrying the weights b b. The inner ends of the arms G are pivotally connected to the cross-head G³.

85 It may be found advantageous in some instances to slightly modify the construction of the automatic pressure-adjuster by constructing the arms F² and G in separate sections and connecting the adjacent sections by means of a turn-buckle, f f, as I have shown in Fig. 2 90 of the drawings. In said figure I have dispensed with the wheels G² and substituted therefor pivoted links g, the ends of the pivots moving horizontally in slots h, formed in suitable guide-plates, h².

95 In operation a sufficient weight, b, is placed upon the weight-holder E to cause the float-

chamber B' to lower, thus opening the valve C³. Gas is thus allowed to pass through the inlet-pipe A to the valve-chamber C⁴, and thence through the valve C³ to the valve-dome D, whence it passes through the openings C⁶ to the float-chamber B', where it exerts its pressure under the roof of the chamber and passes to the service-main A'. As soon as the gas which has been admitted to the float-chamber exerts its pressure beneath the roof of the same, the chamber is raised and the valve C³ partly closed, until the opening of the valve will be sufficient to admit such quantity of gas as will be required, under a pressure to be determined by the amount of weight applied to the weight-holder and the inclination of the rods G. When a greater volume of gas is consumed, the pressure within the float-chamber will be lessened and the chamber carrying the valve will be opened so as to allow the gas to enter more freely, and at the same time the rod E³, carrying with it the cross-head G³, will be lowered, thereby lessening the angle of vertical inclination of the rods G, and the weight is caused to bear more directly upon the cross-head G³, and thence upon the float-chamber, thus requiring a greater pressure within the chamber to counterbalance the same, and the gas will consequently be discharged through the service-main under greater pressure, and it will only return to the original pressure when less gas is consumed, thus allowing a greater quantity of gas to enter through the valve C³ than is required for consumption. The gas thus entering under a higher pressure will instantaneously exert its pressure beneath the roof of the float-chamber, closing the valve C³, and at the same time, by lifting the rod E³ and the cross-head G³, return the arms G to a more horizontal position.

In order to prevent the gas entering at A under varying degrees of pressure from exerting any pressure upon the valve C³, and thereby on the float-chamber B', I construct the valve-chamber in the substantially-conical form shown, the vertical projection of which cone is equal to the superficial area of the valve C³, thereby making it in itself a counter-balance-valve, as will be understood. In case the superficial area of the valve is O, the chamber C⁴ will become a cylinder.

The operation of the automatic pressure-adjuster will be understood by reference to Figs. 2, 3, and 4. The rods F² swing around the points 2, while the rod G swings upon the points 3^a. The points 4 and 5 remain at all times in the same horizontal plane. When the float sinks, and thereby causes the shaft E³ to descend, the weight will be increased gradually until the point 3^a reaches the point 3^b, at which it will attain its maximum pressure, as shown by the position of the point 3^b, which is about one-half the distance between the extreme points 3^a and 3^b, the angle of pressure being lessened at this point about fifteen degrees. Figs. 3 and 4 show the variations in the angle of pressure occasioned by the lengthening or shorten-

ing of the arms F² and G by means of the turn-buckle f, as will at once be evident.

While I have described the valve-chamber C⁴ as conical in form, and prefer such construction, I do not desire to limit myself thereto, as it is evident that the form of the chamber may be modified or changed without departing from my invention. Instead of using turn-buckles for changing the length of the arms, any other suitable appliance adapted to the purpose may be substituted.

It will be observed that the valve is arranged within the float-chamber near the top thereof, and is readily accessible for repairs or other purposes by reason of the top of the dome being made removable, as shown in Fig. 1. This is important.

Having thus described my invention, what I claim to be new, and desire to secure by Letters Patent, is—

1. The combination, with the float-chamber and a removable top therefor, and a valve-chamber in the float-chamber and having near its lower end an outlet communicating with the float-chamber, of a valve within said chamber and accessible from the top of the float-chamber, substantially as and for the purpose described.

2. The combination, with the float-chamber, of a valve chamber therein of increased area at its top and provided at its lower end with an outlet communicating with the float-chamber, substantially as and for the purpose described.

3. The combination, with the float-chamber, of the valve-chamber therein having an outlet near its lower end communicating with the float-chamber and outlets from the valve chamber above the valve into the float-chamber, substantially as described.

4. The combination, with the water-tank and float-chamber, of a weight-support, an adjustable rod carrying said support and engaging the float-chamber, and pivoted connections between said rod and the water-tank, and the roller G², on which the weight-support rests.

5. The combination, with the water-tank and float chamber, of the vertical rod adjustably connected with said float-chamber, a weight-support vertically movable on said rod, a cross-head on said rod directly beneath said weight-support and sustaining the weight of the same, arms pivoted to said cross-head, and arms F², pivotally connecting said arms with the water-tank, substantially as described.

6. The combination, with the inlet-pipe, of an outlet-pipe inclosed within the same and a valve attached to the upper end of the outlet-pipe and serving to close the upper end of the inlet-passage, as set forth.

In testimony whereof I affix my signature in presence of two witnesses.

FREDERICK BREDEL.
